UNITED STATES PATENT OFFICE.

HARRY W. BUNDY, OF DETROIT, MICHIGAN.

METHOD OF MAKING FINNED TUBING.

Application filed July 14, 1927. Serial No. 205,594.

This invention relates to a method of making finned tubing and it has to do especially with a method wherein spiral fin is placed upon a preformed tube.

The method consists in the taking of a tube of any desired character and advancing the tube longitudinally while rotating the same. While the tube is thus handled fin stock is spirally wrapped upon the tube and secured thereto. The fin stock is treated in a novel manner and so that a relatively large contact between the fin and the tube is effected. The invention contemplates a method wherein the fin stock can be wound upon the tube in such a manner as to reinforce the body of the tube thus permitting the use of a preformed tube of relatively thin stock, or a tube which does not have the strength required in the finished finned tube, with the fin stock affording the additional strength required.

In the accompanying drawings:

Fig. 1 is an assembly view showing the method by which the fin tubing is made.

Fig. 2 is an enlarged detail showing how the fin stock is treated prior to being wound upon the tube.

Fig. 3 is a sectional view taken through a roller mechanism which may be employed for pressing the fin stock tightly against the tube.

Fig. 4 is an enlarged section taken on line 4-4 of Fig. 2.

Fig. 5 is a section on line 5-5 of Fig. 1 showing one arrangement of the rollers which press the fin stock against the tube, such rollers having been shown in section in Fig. 3.

Fig. 6 is a sectional view on line 6-6 of Fig. 3 showing the completed tube.

A tube to which the fin stock is to be applied is referenced 1. This tube is disposed between a pair of rollers 2 and 3 which are rotated and which engage opposite sides of the tube and thus cause a rotation of the tube around its central axis. These rollers are indicative of any suitable mechanism for rotating the tube. The direction of rotation of these rollers is indicated by the arrows in Fig. 3. The rollers are preferably disposed at an angle to each other, as clearly shown in Fig. 1, and thus a line contact is had with the opposite sides of the tube. The forward end of the tube advances into the fin applying mechanism.

The advancement of the tube may be effected by suitable driving rollers in engagement with the tube (not shown), or the advancement of the tube may be effected

by utilizing the rotary movement of the tube, as effected by the rolls 2 and 3.

Strip stock 5 is drawn from a supply of stock preferably in the form of a roll (not shown). This strip stock may be tinned previously to being put in the supply roll. However, it may not be tinned in the supply roll and a coating of tin or solder may be applied as the stock is drawn from the supply. This is optional, but I have shown in Fig. 1 the step of tinning the stock after it is drawn from the supply. For this purpose the stock is drawn through an acid bath, a solder bath, and then a cooling water bath in progressive steps, as shown in Fig. 1.

The stock is then drawn over a roller 5, which is merely a guide roller and turns the stock through an angle of about 90°. The stock is then drawn through a pair of rollers 6 for the purpose of bending the stock so that it is angular in cross section. This is best shown in Fig. 4 and it will be noted that the rollers 6 bend the stock so that the stock has one leg portion 7 and another leg portion 8. The bend, as shown, is one of 90° although the angle may be other than 90° as desired. For the purpose of convenience the portion 8 will hereinafter be referred to as the horizontal portion and the portion 7 as the upright portion without in any way intending to limit the angle to 90°. The stock thus bent is drawn through a guide die 10 positioned immediately adjacent the point where the stock is to be wound upon the tube.

In winding the stock upon the tube, the metal of the upright portion must either be drawn or stretched to provide for the varying diameters between the outside of the upright portion and the inner edge thereof, or it may be crimped or corrugated. I have shown a pair of crimping rollers 11 and 12 between which the upright portion of the stock is engaged and corrugated, as shown at 13, in Fig. 6. The roller 11 is mounted upon a suitable shaft 14 which is driven, and the roller 12 may either be an idler or positively driven, as will be determined by the nature of the work.

The speed of rotation of the crimping rollers is coordinated with the rotative movement of the tube so that the strip stock is corrugated and wound upon the tube. The tube with the strip stock thus wound thereon advances through a set of rollers 15. As shown in Fig. 6 there are preferably three

of such rollers to a set, as referenced 15^a, 15^b and 15^c. These rollers are in the form of screws or worms having portions which fit in between the spiral fin, formed by the upright portion of the stock, and press the horizontal portion of the stock tightly against the tube, as shown in Fig. 3. These rollers are preferably positively driven by means of a suitable gear wheel 16 and an idler 17. The speed of rotation of these rollers may be coordinated with that of the rotative movement of the tube so as to cause the advancement of the tube. If this should be done, the previously referred to driving roller 15 could be omitted. On the other hand, these rollers can be held stationary and the rotative movement of the tube through these worm rollers would cause the advancement of the tube inasmuch as the spiral fin engages in the grooves in the worm rollers much after the manner of a screw.

This applies the fin stock to the tube. For the purpose of securing the fin stock to the tube it may be then passed through a heating die to melt the coating of solder on the fin stock and cause the same to adhere to the tube. However, a second coating of solder may be applied to this strip, and this is shown in the drawings, inasmuch as it is thought to be preferred. For this purpose an acid may be sprayed over the finned tube by a suitable nozzle 20, whereupon the tube advances through a solder lifting device 21. This solder lifting device may be of any one of the well known constructions for lifting molten solder from the pot 22 and pouring the molten solder over the tube. The solder is kept molten by suitable burners 23. If desirable, the tube may be first passed through a sweating die to melt the coating of the fin stock, and the second coating may be applied on the outside. However, the sweating operation may be omitted inasmuch as the heat present in the solder bath 21 may be sufficient to melt the coating of solder on the fin stock thus simultaneously applying solder bath and melting the coating of solder on the fin stock.

Following this step, excess solder may be blown off by air supplied to a suitable nozzle 25 and directed against the tube. The tube may then be cooled by passing through a cooling water bath 26. Following this, another set of rollers 27 may be utilized for insuring perfect formation of the completed tube. These rollers may be much the same as the set of rollers 15.

Preferably, relatively long lengths of tube will be inserted into the fin applying mechanism, and if it is desirable to have the finished fin tubing in short lengths, the tube may be cut off in such proper short lengths as it advances through the rollers 27. This may be

accomplished by an automatic or hand cut off device not shown.

Inasmuch as separate lengths of preformed tube are used, the problem arises as to how to originally secure the fin stock to the tube when it first enters the fin applying mechanism. The preferred manner of doing this is that of providing the crimping rollers 11 and 12 so as to give sufficient curl to the stock to cause the stock to curl tightly around the tube. In other words, the curl given to the stock by the crimping rollers can be made so that the interior diameter of this curl is normally slightly less than the outside diameter of the tubing. Thus the fin stock will tightly grip the tube under a slight spring pressure. This is sufficient to hold the tube and the fin stock in proper relation as it advances and until they are secured together by the solder. After the first length of tube has been started, a second length, and all following lengths, may be started by merely causing the forward end of the following lengths to abut directly against the rear end of the tube just preceding, so that the fin stock is wound continuously and covers the break between the two tubes. After the fin stock is applied, the tubes can be separated by cutting through the fin stock at the abutting ends of two lengths of tube. On the other hand, a thimble device can be used to grip a portion of the forward end of a length of tube and the first convolution of the fin stock.

In practicing the method it is preferred to wind the stock on the tube so that the adjacent convolutions are in substantially abutting relation. In other words, the outer edge of the horizontal portion in each convolution lies against or very close to the point of junction of the horizontal portion and the upright portion in the next adjacent convolution. When the solder or other sealing metal is applied a secure connection is made between the convolutions. Thus, there is a spiral reinforcing band covering all parts of the preformed tube. This adds strength to the tube and permits the use of tube made from relatively light stock.

I claim:

The method of making finned tubing which consists in moving a tube longitudinally, rotating the tube while it is so moving, drawing strip stock from a supply, bending this strip stock so that it is angular in cross section to provide an upright and a horizontal portion, crimping or corrugating the upright portion, winding this stock on the tube with the upright portion forming a continuous spiral fin on the tube and with the horizontal portion directly engaging the body of the tube to form a spiral band on the tube.

In testimony whereof I affix my signature.

HARRY W. BUNDY.
